HAIR CURLER

Walter H. Hermsdorf, Chicago, Ill., assignor to
 Chain Store Products Corporation, Chicago,
 Ill., a corporation of Delaware

Application October 24, 1935, Serial No. 46,545

12 Claims. (Cl. 132—33)

The present invention relates to improvements in hair curling devices of the type that do not require application of heat, and more particularly to devices that are characterized by 5 a hollow cylindrical body portion formed with an elongated open end slot in which the end of a strand of hair is slipped preparatory to winding the strand of hair about the body portion for forming a curl. In the use of devices of 10 this general character a "Bobby" pin or the like fastening element is applied so that one leg of the hairpin is inserted inside of the hollow body portion, and the other outside and over the ringlet or curl of hair. The curling device may 15 then be removed, and the hairpin will secure the strand of hair in curled shape.

At the present time there are on the market several devices of this general type which are characterized by a rigid cylindrical hollow body 20 portion on which hair is wound, and which is formed with an elongated open end slot of definite size. Some of such devices in order to be used practically and easily, make it necessary that the strands of hair to be curled are of the 25 same predetermined thicknesses so that the strand of hair may be snugly engaged by the edges of the elongated slot to provide adequate frictional resistance to assist in initiating the winding of the strand of hair about the body 30 of the curler. Other devices of this general type are formed with spring gripping elements disposed inside of the tubular body for gripping the end of the strand of hair preparatory to formation of the curl. Manifestly these types 35 of devices do not allow any appreciable latitude in selecting strands of hair of desired thicknesses for curling. Strands of hair that are too thick cannot be inserted into the slots, and strands of hair that are relatively thin when 40 inserted in the slot will not frictionally engage the edge of the slot, of certain constructions, for assisting in initiating the winding of the strand of hair around the body in making a curl.

It is therefore a primary object of my invention 45 to form the hollow cylindrical body, on which the strand of hair is wound, of two longitudinally extending substantially semi-circular cross sectional members resiliently connected together at a pair of adjacent ends for permitting yielding separation of the other ends thereof defining the elongated slot, so that the edges of said slot may engage with a slight amount of friction strands of hair of a substantial range of 50 thicknesses for securing the end of the strand

preparatory to curling it around the body member.

Another object is to produce an improved device of this character which may be quickly and easily applied to a strand of hair and removed 5 therefrom after the curl has been formed.

A further object resides in the provision of an improved hair curling device of this general character wherein the edges of the open end elongated slot for receiving the end of the strand 10 of hair, are resiliently urged toward each other and in which a stop is provided for limiting the extent of insertion of a strand of hair in the slot.

A still further object of my invention is to 15 produce an improved device of the above mentioned type which is relatively simple in construction, economical to manufacture, and which is highly efficient in carrying out the purposes for which it was designed.

Referring now to the drawing, Fig. 1 is a view 20 in side elevation of the device embodying the present invention.

Fig. 2 is a longitudinal section through the center of the device taken at line 2—2 on Fig. 3. 25

Fig. 3 is a transverse section through the device, taken as indicated at line 3—3 on Fig. 1.

Fig. 4 is a side view of the device in the process of forming a curl and indicating the method 30 of securing the curl in shape.

My improved form of curling device includes a tubular body member 10 of substantially circular cross section and which is composed of two longitudinally extending substantially semi-circular members 11, formed from light weight 35 metal, such as aluminum. These members are secured in proper edge-to-edge relation to each other by a cap 12, encompassing a pair of corresponding ends of said members. The edges of said body members at their planes of contact, are cut away to form a pair of diametrically 40 opposed elongated slots 13 opening from the end opposite said cap 12, and extending a substantial portion of the length of said members. The slotted ends of said members are cut back as indicated at 14, to form a flaring mouth opening 45 into the elongated slots 13 to facilitate insertion of a strand of hair therein. It will be noted that the elongated slots 13 are of V-shape formation and the purposes and advantages of 50 which will hereinafter be referred to.

The cap member 12 is formed of resilient material, such as relatively soft rubber, so as to permit lateral flexing of the body members 11 and opening the V-slots 13 (as indicated in dotted 55

lines in Fig. 2), to permit the slots to accommodate strands of hair of substantial thickness. To insure against possible displacement of the body members 11 relative to each other, I employ a tubular sleeve 15 which is disposed inside of said body members, at the end encompassed by the cap, and said sleeve is formed with a pair of diametrically opposite apertures 16 in which engage pivot embossments 17 stamped inwardly out of the respective body members 11. These projections 17 are of substantial length and the apertures 16 of ample size so as to permit free and unobstructed pivotal movement of said members, against the light reaction of the resilient encompassing band of the enclosing cap 12. The forward end of the tubular body 15 terminates in close proximity to the apex of the elongated V-slots 13 and serves the purpose of limiting the extent of insertion of strands of hair into the slots and thus avoids entanglement and snagging of individual hairs in the curling device.

In using my device one or more strands of hair may be curled by grasping their ends, holding them slightly taut, and slipping said ends into the elongated open end slots 13 of the tubular body, and the flaring mouth defined by the cut away portions 14 will facilitate directing the strands of hair into the slots. Because of the V-shaped formation of the slots 13, and due to the resilient action of the cap 12, opposing lateral displacement of the body members 11, it will be apparent that the edges of the body members 11, defining the elongated slots 13 will exert a slight frictional pressure on the strands of hair when inserted therein so as to assist in initiating the rotation of the curling device for winding the strand of hair about the tubular body to form curls or ringlets. By virtue of the resilient action of the body members, strands of hair of different thicknesses may be conveniently inserted into and withdrawn from the elongated slots of my improved device, and due to the V-formation of the slot it will be manifest that relatively thin strands of hair may be inserted so as to be frictionally engaged by the edges of the slot to hold the strand of hair preparatory to winding onto the body portion in forming a curl.

50 When the device has been rotated to wind the hair about the body of the curler and the curler is disposed snugly against the scalp, a retaining device in the nature of a hairpin such as a "Bobby" pin indicated at 18 in Fig. 4, is then employed by inserting one leg inside the open end of the curler and the other leg outside and over the curl of hair, and serves to retain the hair in curled shape. The curler may then be easily withdrawn by pushing the curl off of the body 10, and the retaining member 18 will hold the curl in shape. When the curler is withdrawn, the curl falls back over the "Bobby" pin substantially concealing it. If the curls are formed by my device when the hair is damp or wet, the retaining members may be permitted to remain in place for holding the curls in shape until the hair is dry and they may then be removed if desired.

Although I have shown and described a preferred embodiment of my invention it will be manifest that it is capable of modification and re-arrangement of parts without departing from the spirit and scope thereof. I do not, therefore, wish to be understood as limiting my invention to the specific construction herein shown and de-

scribed, except as indicated in the appended claims.

I claim as my invention:

1. A hair curler including a tubular body composed of a pair of elongated, substantially semi-circular members positioned one on another and having portions cut away to form a pair of diametrically opposed, open end elongated slots for receiving a strand of hair therein, preparatory to curling, and means associated with said members for yieldingly urging one toward the other for causing the edges of said slots to exert slight frictional pressure on the strand of hair when it is first inserted in the slots to facilitate curling the hair around the body. 15

2. A hair curler including a tubular body comprising a pair of elongated, substantially semi-cylindrical members positioned one on another and having portions cut away to form a pair of diametrically opposed open end elongated slots 20 for receiving a strand of hair therein preparatory to curling it around said body, and means at the ends of said members opposite the slots providing pivotal connections for said members so that the slotted ends thereof may swing laterally toward or away from each other. 25

3. A hair curler including a tubular body comprising a pair of elongated, substantially semi-cylindrical members positioned one on another and having portions cut away to form a pair of 30 diametrically opposed open end elongated slots for receiving a strand of hair therein preparatory to curling it around said body, means at the ends of said members opposite the slots providing pivotal connections for said members so 35 that the slotted ends thereof may swing laterally toward or away from each other, and resilient means associated with said members adapted to yieldingly oppose lateral separation of the slotted ends of said members. 40

4. A hair curler including a tubular body comprising a pair of elongated, substantially semi-cylindrical members positioned one on another and having portions cut away to form a pair of 45 diametrically opposed open end elongated slots for receiving a strand of hair therein preparatory to curling it around said body, means at the ends of said members opposite the slots providing pivotal connections for said members so that the slotted ends thereof may swing laterally toward 50 or away from each other, and a band of resilient material encompassing said members intermediate the slots and their pivotal connections, for yieldingly opposing lateral separation of the slotted ends of said body members. 55

5. A hair curler including a tubular body composed of a pair of elongated, substantially semi-cylindrical members positioned one on another and having portions cut away to form a pair of 60 diametrically opposed open end slots for receiving a strand of hair therein preparatory to curling it around said body, and a tubular supporting member disposed inside of the body members at the end opposite the slots, said tubular member and body members being pivotally connected to permit lateral separation of the slotted ends of said body members. 65

6. A hair curler including a tubular body composed of a pair of elongated, substantially semi-cylindrical members positioned one on another 70 and having portions cut away to form a pair of diametrically opposed open end slots for receiving a strand of hair therein preparatory to curling it around said body, a tubular supporting

member disposed inside of the body members at the end opposite the slots, said tubular member and body members being pivotally connected to permit lateral separation of the slotted ends of said body members, and resilient means associated with said body members and adapted for yieldingly opposing such lateral separation of the body members.

7. A hair curler including a tubular body composed of a pair of elongated, substantially semi-cylindrical members positioned one on another and having portions cut away to form a pair of diametrically opposed open end slots for receiving a strand of hair therein preparatory to curling it around said body, and a tubular supporting member disposed inside of the body members at the end opposite the slots, said tubular member and body members being pivotally connected to permit lateral separation of the slotted ends of said body members, one end of said tubular supporting member terminating in close proximity to the end of the elongated slots and serving as a stop for limiting the extent of insertion of a strand of hair in said slots.
8. A hair curler including a tubular body composed of a pair of elongated, substantially semi-cylindrical members positioned one on another and having portions cut away to form a pair of diametrically opposed open end elongated slots of substantial length for receiving a strand of hair therein preparatory to curling, and a cap for enclosing the ends of said body, opposite the slots, said cap being of resilient material having a band portion encompassing said body members and serving to yieldingly oppose lateral separation of the slotted ends of said body members.
9. A hair curler including a tubular body com-

prising a pair of elongated, substantially semi-cylindrical members positioned one on another and having portions cut away to form a pair of diametrically opposed open end elongated slots of V-shape formation, for receiving a strand of hair therein preparatory to curling it around said body, and means at the ends of said members opposite the slots providing pivotal connections for said members so that the slotted ends thereof may swing laterally toward or away from each other. 10

10. A hair curler including a tubular body composed of a pair of elongated substantially semi-cylindrical members positioned one on another and having portions cut away to form a pair of diametrically opposed elongated slots of V-shape 15 formation for receiving a strand of hair therein, preparatory to curling it around said body, and means associated with said body members for yieldingly urging them toward each other, so as to cause the edge portions of said members defining said slots to exert slight frictional pressure on the strand of hair when it is inserted therein.

11. A hair curler comprising in combination, a pair of substantially semi-cylindrical members adapted to be juxtaposed edge to edge, and a resilient cap circumscribing said members and impelling said members toward each other, said members having opposite edges cut away to provide oppositely disposed slots. 25

12. A hair curler comprising in combination, a pair of substantially semi-cylindrical members adapted to be juxtaposed edge to edge, and a resilient cap surrounding a pair of corresponding ends of said members for yieldingly opposing separation of the opposite ends of said members. 30 35
